UNITED STATES PATENT AND TRADEMARK OFFICE
CERTIFICATE OF CORRECTION

PATENT NO. : Des. 523,891 S
APPLICATION NO. : 29/210838
DATED : June 27, 2006
INVENTOR(S) : Chun-Ying Tu

Page 1 of 1

It is certified that error appears in the above-identified patent and that said Letters Patent is hereby corrected as shown below:

On the Title Page, item (73) should read -- Assignee: Hi-Touch Imaging Technologies Co., Ltd --.

Signed and Sealed this

Thirteenth Day of March, 2007

A handwritten signature in black ink, appearing to read "Jon W. Dudas", is centered within a rectangular box with a dotted background.
